(57) **CLAIM**

The ornamental design for a utensil rest, as shown.

DESCRIPTION

FIG. 1 is a top, side perspective view of a utensil rest showing my new design;

FIG. 2 is a top plan view thereof;

FIG. 3 is an end view thereof;

FIG. 4 is a cross-section view on line 4—4, in FIG. 7

FIG. 5 is a cross-section view on line 5—5; and, in FIG. 7

FIG. 6 is a cross-section view on line 6—6; and, in FIG. 7; and,

FIG. 7 is a top plan view thereof.

The broken lines are for illustrative purposes only and form no part of the claimed design.
